(57) CLAIM

I claim the ornamental design for a video game case, as shown and described.

DESCRIPTION

FIG. 1 is a perspective view of a video game case embodying the new design;

FIG. 2 is a front elevational view thereof;

FIG. 3 is a rear elevational view thereof;

FIG. 4 is a side elevational view thereof; the

FIG. 5 is another side elevational view thereof;

FIG. 6 is a top view thereof; and,

FIG. 7 is a bottom view thereof.

The broken lines illustrate the disclaimed portions of the design and form no part of the claimed design.
